UNITED STATES PATENT OFFICE.

CHARLES E. WICKLIFFE, OF NEW YORK, N. Y., ASSIGNOR OF ONE-FOURTH TO THOMAS
McMURRAY AND ONE-FOURTH TO JOHN JENNERICH, BOTH OF NEW YORK, N. Y.

WINDOW-SHADE BRACKET.

1,358,270.

Specification of Letters Patent.

Patented Nov. 9, 1920.

Application filed March 24, 1920. Serial No. 368,214.

To all whom it may concern:

Be it known that I, CHARLES E. WICKLIFFE, a citizen of the United States, and resident of the borough of Manhattan, city, county, and State of New York, have invented certain new and useful Improvements in Window-Shade Brackets, of which the following is a specification.

This invention relates to improvements in brackets for supporting shade rollers, and has for its object to provide a bracket of simple and inexpensive construction which may be readily stamped, or otherwise formed, from sheet metal and which may be readily and securely fastened to a window frame.

In the drawings,

Figures 1 and 2 are perspective views of brackets embodying the invention, designed for use at opposite sides of a window frame to removably support a shade roller;

Fig. 3 a front elevation showing the brackets applied to a window frame and supporting a shade roller;

Fig. 4 a horizontal section on the line IV—IV of Fig. 3; and

Fig. 5 a perspective view showing the right hand bracket secured to the window frame.

The two brackets are stamped, or otherwise formed, of bendable sheet metal. Each bracket comprises a plate 1, preferably elongated vertically as shown, and having a long and narrow bendable extension or arm 2 formed integrally therewith. The arm 2 extends horizontally from one of the vertical side edges of the plate 1, preferably at a point intermediate the upper and lower ends of the plate, as shown, and is preferably formed with a widened or flared outer end portion 3 having a vertical end edge parallel with the side edges of plate 1. The plate 1 is provided with an aperture 4, preferably in horizontal alignment with the bendable arm or tongue 2, through which the shank of a tack, screw, or nail may be driven, as hereinafter described.

The plate 1 of the left hand bracket is formed with a laterally offset substantially U-shaped portion 5 at its upper end and the plate 1 is formed with a similar offset portion 6 at its upper end. The offset portions 5 and 6 are formed by pressing a portion of each plate laterally beyond the plane of the main body portion of the plate, and said

offset portions project from opposite faces of the plates to adapt the brackets for use at opposite sides of a window frame. The offset portion 5 of the left hand bracket is formed with a vertical slot 7 which is open at its upper end, and the offset portion 6 of the right hand bracket is formed with a circular aperture 8.

The brackets are designed to be shipped and sold in flat form in pairs, as shown in Figs. 1 and 2. To apply the brackets to a window frame, the flared ends 3 of the tongues or anchoring members 2 are forced or driven between the abutting faces of the window frame 9 and the usual sash-retaining strips 10 at opposite sides of the window frame and the tongues 2 are then bent closely around the inner edges of the strips 10 until the plates 1 lie flat against the inner faces of the strips 10. Tacks 11, or other suitable fastening devices, are then driven or screwed into the strips 10 with their shanks passing through the apertures 4 in the plates 1.

The broad frictional bearing of the flared ends 3 of tongues 2 on the strips 10 and window frame 9 and the broad frictional bearing of plates 1 on strips 10 serve to prevent rocking of the brackets about the tacks 11 as pivots and also assist in resisting vertical or horizontal sliding of the brackets on the strips 10. These broad bearing surfaces also prevent the plates 1 from swinging or tilting away from the inner faces of strips 10. By anchoring the tongues 2 between the window frame and sash-retaining strips the brackets may be securely held to the window frame by a single tack or other small fastening device. By providing relatively long bendable tongues or anchoring arms the brackets may be attached to window frames having sash-retaining strips of different thickness.

While I have shown the offset portions 5 and 6 of U-shape, and as being formed at the upper ends of plates 1, it will be obvious that both the shape and location of the offset portion may be changed. A shade roller of the usual construction, having the usual cylindrical journal at one end and the usual flattened journal at the other end, and a shade 12 rolled thereon, may be removably mounted in the brackets by inserting the cylindrical journal in the aperture 8 and dropping the flattened journal in the slot 7.

It will be obvious also that the opening 4 may be omitted and that the bracket may be attached to a window without employing a tack or screw, since ordinarily the end 5 3 of the anchoring tongue 2 will be so securely clamped between the abutting faces of the frame 9 and strip 10 that the bracket will be firmly held in place and it will be unnecessary to employ additional fastening 10 devices.

What I claim is:

1. A one-piece sheet metal shade bracket comprising a flat vertically elongated plate having a portion thereof adjacent one end 15 pressed laterally and provided with a bearing for a shade roller spindle, and a narrow integral bendable anchoring arm extending from one side edge of the plate and having smooth flat side faces to adapt the 20 free end of the arm to be forced between the side member of a window frame and the inner face of a sash-retaining strip, the free end of said bendable arm being widened vertically and the plate being 25 provided with an aperture substantially midway its upper and lower ends to permit a fastening device to be inserted through the plate to secure the plate to the outer face of a sash-retaining strip.
- 30 2. A sheet metal shade bracket comprising a flat plate having a portion thereof pressed laterally and provided with a roller-

spindle bearing, said plate being formed with a smooth flat integral anchoring arm extending from one side edge of the plate 35 the free end of which is adapted to be frictionally clamped between a side member of a window frame and the inner face of a sash-retaining strip, said arm being bendable around the edge of a sash-retaining 40 strip, and said flat plate being provided with a nailing aperture to adapt the same to be fastened flush against the outer face of the sash-retaining strip.

3. A flat sheet metal shade bracket comprising a plate a portion of which is pressed laterally and provided with a bearing for a shade roller spindle, said plate being provided with a smooth, flat, relatively narrow, integral anchoring arm extending 50 from one side thereof in the same plane and adapted to be driven between a side member of a window frame and a sash-retaining strip, the outer end of said arm being widened and the narrow portion of 55 the arm being bendable around the edge of a sash-retaining strip to place the plate flush with the opposite face of the strip from the widened anchoring end of the arm.

In testimony whereof I hereunto affix my signature.

CHARLES E. WICKLIFFE.
